FASTENING DEVICE FOR CONTAINER COVERS

August H. Riess, Lawndale, Calif.

Application May 26, 1952, Serial No. 290,019

3 Claims. (Cl. 292—29)

1

This invention relates to containers, and particularly to a mechanism for securing a cover to the container.

The covers of conventional receptacles for the collection and removal of waste products are ordinarily easily removable. Animals may often interfere with the orderly and sanitary collection of waste material by simply overturning the can, and thereby undesirably removing the cover and the contents.

It is an object of this invention to overcome these problems by providing a simple and reliable mechanism for insuring against accidental removal of the cover, or against disturbance by animals.

It is another object of this invention to provide an improved releasable latch for a cover of a container.

It is another object of this invention to provide a latch mechanism cooperable with the rim of a conventional receptacle, and having its operating parts mounted only upon the cover. Specifically, it is an object of this invention to provide a cover having an improved latch that is standardized for cooperation with a container without providing any additional mechanism for the container proper.

It is still another object of this invention to provide an improved latch mechanism of this character that is of extremely simple construction, readily assembled, and of economical manufacture.

This invention possesses many other advantages, and has other objects which may be made more clearly apparent from a consideration of one embodiment of the invention. For this purpose, there is shown a form in the drawings accompanying and forming part of the present specification. The form will now be described in detail, illustrating the general principles of the invention; but it is to be understood that this detailed description is not to be taken in a limiting sense, since the scope of this invention is best defined by the appended claims.

Referring to the drawings:

Figure 1 is a pictorial view of a container employing a cover that embodies the present invention;

Fig. 2 is an enlarged plan view of the cover construction illustrated in Fig. 1, with a part of the cover broken away;

Fig. 3 is an enlarged fragmentary view, showing the operating mechanism of the present invention, the phantom lines illustrating another adjusted position of the mechanism;

2

Fig. 4 is a sectional view, taken along the plane indicated by the line 4—4 of Fig. 3; and

Fig. 5 is fragmentary sectional view, taken along the plane indicated by the line 5—5 of Fig. 2.

A customary container 10 is illustrated in Fig. 1 that is provided with the usual pivotally mounted bail 11. A cover 12, provided with the usual annular flange 17, is shown most clearly in Fig. 5, telescopes over the end of the container 10, thereby closing it.

Containers of this general character which are utilized for the disposal of food waste, cans, bottles, or other refuse, are customarily provided with an annular beaded edge extending about the opening of the container. Such a bead 13 is illustrated in Fig. 5 and extends outwardly of the body of the container 10.

The present construction utilizes this bead 13 as one of the parts of a latch construction, preventing accidental removal of the cover 12. Thus, as illustrated in Fig. 5, a latch member 14 has a detent 15 formed at the end thereof and passing through an aperture 16 in the annular flange 17 of the cover 12. Two similar latching members 14 are provided for the cover 12 at diametrically opposite portions of the cover. The detents 15 are movable toward and from each other. Thus, the distance between the detents diametrically across the cover can selectively be made less or greater than the maximum diameter of the bead 13. Accordingly, the detents 15 cooperate with the bead 13 for preventing removal of the cover 12.

Each of the latching members 14 may be conveniently formed by bending a rod substantially in hooked shape for conforming to the configuration of the cover 12 and the flange 17. Each rod 14 extends along the upper side of the cover and terminates slightly past the center thereof. They are shiftable radially outwardly and inwardly for their latching function.

For this purpose, a crank member 18, of substantially disc form, is provided for moving the rods 14. This crank member 18 is pivotally mounted centrally of the cover 12 by any appropriate means, such as pins, bolts or the like. In the present instance, a nut and bolt construction 19 and 20 passes through the crank 18 and cover 12, respectively. A washer 21, of a substantial thickness, spaces the crank member 18 above the cover 12. The inner ends 23 of the rods 14 extend through appropriate apertures 24 at diametrically opposite portions of the crank 18. The apertures 24 eccentrically mount the rods 14,

whereby there is provided longitudinal or radial component of movement therefor. The ends of the rods 14 may be upset to prevent removal from the crank 18, and they are accommodated within the space between the crank 18 and the cover 12, as defined by the washer 21.

Rotational movement of the crank 18, facilitated by the aid of a bent-out thumb piece 22, thus serves to move the rods 14 radially outwardly or inwardly of the cover 12. Such movement positions the detents 15 radially outwardly or inwardly with respect to the flange 17 of the cover 12, for preventing or permitting removal of the cover from the can proper 10.

The rods 14, as illustrated in Fig. 2, are of a length, such that they would ordinarily be continuously reciprocable upon continued rotational movement of the crank 18. However, provisions are made for confining the rods for movement only through a portion of such complete cycle.

Thus, the detents 15 are upset, as at 28, thereby limiting outward movement of the rods, corresponding to the phantom line position illustrated in Fig. 3. Furthermore, movement of the rods to position the detents 15 inwardly of the flange 17 is also limited. Thus, the rods 14 are so oriented that edges 26 of a customary handle 27 are interposed in the path of movement of the rods 14, thereby limiting clockwise movement of the rods from the phantom line position. The edges 26 will be most effective for this purpose if the rods 14 at the instant of contact therewith have substantially maximum arcuate components of movement about their mounting on the cover flange 17. To insure such maximum arcuate movement, the rods 14 have bends 28a whereby the apertures 24 are then at substantially the maximum distance from the respective apertures 16 of the flange 17.

When the rods 14 are positioned in the clockwise position, corresponding to latching relation, of the crank 18, provisions are made for maintaining the parts in such position, and thereby preventing accidental opposite movement. For this purpose, yieldable restraints or 45 projections in the form of dimples 25, extending upwardly of the crank 18, engage on that side of the rods 14 opposite the edges 26. This produces a slight bowing of the rods 14, as they move between latching and unlatching position 50 over these dimples or projections 25. The crank 18, therefore, must be intentionally manipulated to overcome the resilient restraint imposed upon the rods by the dimples 25 against the edges 26 of handle 27 in moving the members out of the 55 full line position. The edges 26 and dimples 25, therefore, cooperate to determine a locked position of the latching members.

The entire construction is such that it may easily be installed on a conventional cover construction. Thus, appropriate apertures for the detents 15 and the pivotal mounting for the crank 18 need be provided in the cover. Of these, the aperture for the pivotal mounting is usually present in conventional trash cans. The nut and bolt construction 19, 20, which serves as a pivotal mounting, is the only positive connection for the latching structure.

The inventor claims:

1. In a latch mechanism: a cover having an 70 annular flange; a pair of latching members, each having a detent passing through said flange at

substantially diametrically opposite portions of said flange, said detents extending inwardly of said cover; a crank pivotally mounted on said cover; means pivotally securing the other ends 5 of said latching members eccentrically of said crank for movement of said detents with respect to said cover in accordance with the angular positioning of said crank; abutment means carried by the cover and engageable with said latching members for determining a limiting angular position of said crank corresponding to inward positioning of said detents; and a pair of restraint members carried by said crank, said restraint members being normally in the paths of angular movement respectively of said latching members upon movement of said latching members from a position corresponding to the inward position of the detents, one of the pairs of members being yieldable to permit movement of said latching members over said restraint members upon the application of a turning torque on said crank.

2. In a latch mechanism: a cover having an annular flange and a handle immovably secured to said cover; a pair of latching members, each having a detent passing through said flange at substantially diametrically opposite portions of said flange, said detents extending inwardly of said cover; a crank pivotally mounted on said cover; means pivotally securing the other ends of 30 said latching members eccentrically of said crank for movement of said detents with respect to said cover in accordance with the angular positioning of said crank; said latching members being so located that said handle engages said latching members for limiting movement of said latching members when said detents are positioned inwardly; and yieldable restraints carried by said crank and engageable with said latching members for releasably maintaining said latching members against said handle.

3. In a latch mechanism: a cover having an annular flange and a handle having ends immovably secured to said cover at places spaced from the center of said cover; a pair of substantially symmetrically disposed latching members, each having detents passing through said flange at places on said flange substantially radially aligned with said ends of said handle, respectively; a crank centrally pivotally mounted on said cover; means pivotally securing the other ends of said latching members to said crank for movement of said detents inwardly and outwardly of said flange; said ends of handle engaging said latching members, respectively, for determining a limiting inward movement of said detents; and a pair of projection members with respect to which said latching members are relatively movable, one pair of members being yieldable, said projection members being engageable with said latching members respectively for releasably maintaining said latching members in said limiting position.
